COAXIAL-TYPE FILTER

John S. Foster, Jr., Montreal, Quebec, Canada,
assignor to United States of America as represented by the Secretary of War

Application April 2, 1946, Serial No. 659,107

5 Claims. (Cl. 178—44)

1

This invention relates to radio frequency filters of the coaxial type and more particularly to a band pass filter for use within the microwave range of frequencies. Heretofore, coaxial type filters, while being relatively simple in design, have been difficult to construct and have required laborious methods of assembly.

It is one of the objects of the present invention to provide a filter of the coaxial type which overcomes these disadvantages.

It is another object of the invention to provide a novel filter having individual filter sections in which the several filter sections are assembled simply and accurately, and are capable of being easily replaced.

It is still another object of the invention to provide a microwave filter having band pass characteristics comprising a plurality of removable filter sections.

For a better understanding of the invention together with other and further objects thereof, reference is had to the following description, taken in connection with the accompanying drawing, in which:

Fig. 1 is a longitudinal sectional view of the filter according to one embodiment of the present invention;

Fig. 2 is a longitudinal view of an individual unit of the filter of Fig. 1; and

Fig. 3 is a schematic diagram showing the equivalent circuit of the filter of Fig. 1.

In general, the filter 10 according to this invention, and shown in Fig. 1, is similar to the conventional coaxial type filter in that it utilizes concentric capacitors as the capacitor elements and sections of conductor line as the inductance elements. As shown, filter 10 generally comprises a plurality of internal sections 11 and two end sections 12, one at each end. Each internal section 11 (Fig. 2) comprises a short section of thin walled insulating material 13 generally in the form of a hollow cylinder. Two spaced disk members or short cylindrical members 14 of electrically conductive material are connected at their centers by a length of fine wire 15. The disk members 14 are positioned with their planes substantially perpendicular to the longitudinal axis of filter 10 and are so positioned that their circumferential surfaces fit snugly within the inner surface of the cylinder of insulating material 13. If desired the inner surface of cylinder 13 may be provided with two shoulders 13' against which disks 14 may bear thereby being maintained in proper spaced relation. The wire 15 is stretched taut between the two disk members 14

and then soldered to form a secure connection to the center portions of disks 14. The wire 15 also serves to prevent displacement of the disks 14 thereby holding the components of the unit or section 11 together.

Each of the end sections 12 consists of a center conductor 16 firmly mounted centrally of a block 17 of insulating dielectric material and of generally cylindrical cross-section. The free or outer end 16' of the center conductor 16 extends beyond the block 17. Conductor 16' may be of hollow or resilient construction adapted to receive the center conductor of a coaxial transmission line to which the filter may be attached. Fitted transversely in the hollow cylindrical inner end portion 18 of block 17 is a short disk or cylindrical member 19 similar in construction and mounting to the disk member 14 of the internal filter section 11. Disk member 19 is spaced from the inner end of center conductor 16 and a length of fine wire 20 is stretched taut and soldered at each end thereof to the centers of conductor 16 and of disk member 19 thus effectively holding the disk securely and electrically connecting the center conductor 16 to disk member 19.

The internal sections 11 and end sections 12 are adapted to be received snugly within metallic tube 21 which forms the outer conductor of filter 10.

In assembling filter 10, the individual sections as shown in Fig. 2 are fitted together so that the disk members 14 of adjacent sections 11 are spaced slightly apart. The end sections are then placed so that the disk members 14 and 19 are slightly spaced apart axially of the filter 10 and the whole is inserted in metallic tube 21 or alternatively the sections 11 and 12 may be inserted in proper sequence into tube 21. If desired and to facilitate connection to a coaxial transmission line in a circuit of a communication or radio object locating system, an R.-F. connector 22 may be secured to the free ends of end sections 12. R.-F. connectors 22 may comprise generally a hollow cylindrical member having an inner end portion 23 adapted to fit snugly within the end of metallic tube 21 and having a bore 24 therethrough to accommodate the end portion 16' of center conductor 16 and the inner conductor of the transmission line to be connected. The outer circumferential portion of the R.-F. connector 22 may, if desired, be provided with screw threads for engagement with the end portions of the coaxial transmission line to which the filter is connected.

As thus assembled, it will be seen that filter 10

comprises an outer conductor in the form of a metallic tube 21, an inner conductor formed by the conductor members 16 and the conducting wires 15 which comprise the inductance elements of the filter. Thus the series inductance is furnished by the fine wire members 15. In this construction, the shunt capacitance is furnished by the disk members 14 and 19 which are spaced slightly, by means of the insulating material, from the inner surface of the outer conductor metallic tube 21, while series capacitance exists between the closely adjacent disks 14 and between the disks 14 and 19. Thus, the filter 10 has the characteristics shown in the equivalent circuit of Fig. 3 where like numerals indicate like parts. While there have been shown only two individual units 11, it will be obvious that filter 10 may comprise any number of individual sections 11. In general, the more individual units provided, the more the accentuation of the pass band may be achieved.

The design and dimensions of the various components of filter 10 as described may be determined according to any desired filter design method, for example, according to the method as described in the co-pending application of Seymour B. Cohn, Serial No. 658,939, entitled "Filter", filed April 2, 1946. In the design of microwave band pass filters such as filter 10 of the present invention, the use of a high impedance section of line in the neighborhood of 200 to 300 ohms is often required. The mechanical construction as described according to this invention permits a line characteristic impedance of 200 to 500 ohms with satisfactory results.

It will be understood that a filter constructed according to the invention as hereinbefore described is adapted to be very simply and accurately constructed and the units easily replaced. The components of such a filter are unique in that few materials are used and the machine operations and assembly are very simple, necessitating only lathe and soldering operations. It will also be understood that the several components of the filter 10 may be accurately held in position without necessitating the use of close tolerances and laborious assemblies which have been heretofore necessary with filters constructed with methods heretofore known.

While there has been described what is at present considered the preferred embodiment of the invention, it will be obvious to those skilled in the art that various changes and modifications may be made therein without departing from the invention.

What is claimed is:

1. A band-pass filter of the coaxial type for use within the microwave range of frequencies of electromagnetic energy comprising, in combination, a metallic tube forming the outer conductor, a plurality of removable filter sections slidably mounted in said tube, said filter sections comprising a plurality of internal sections arranged longitudinally of said tube and two end sections, each of said internal sections comprising a hollow cylinder of insulating dielectric material adapted to slide snugly into said tube, two short circular disk members of electrically conductive material mounted concentrically of said tube and cylinder with their circumferences snugly fitting within opposite ends of said cylinder and a fine

wire secured to, and electrically connecting, the centers of said disks, each of said end sections comprising a cylindrical block of insulating dielectric material adapted to fit within said tube, one end of said block being shaped as a hollow cylinder, its opposite end having an axial bore therethrough, a solid conductor located snugly in said bore, a disk member of electrically conductive material adapted to fit snugly and concentrically within said hollow cylindrical end portion and a fine wire secured to and electrically connecting the centers of the inner end of said conductor and of said last-mentioned disk members, the disk members of adjacent sections, when 15 in assembled position within said tube being slightly spaced apart to afford series capacitance elements, shunt capacitance being afforded between the circumferences of said disk members and said tube, and series inductances being afforded by said conductors and said wires, and means for connecting the ends of said filter to lengths of coaxial transmission line in a circuit.

2. A filter as claimed in claim 1 wherein said wires are stretched taut and soldered to the center portions of said disks and said conductors thereby being effective to maintain said disks in position and thus the components of each of said sections together as a unit.

3. A band-pass filter of the coaxial type for use within the microwave range of frequencies of electromagnetic energy comprising a metallic tube forming the outer conductor, a plurality of removable filter sections slidably mounted in said tube, each of said filter sections comprising spaced concentric capacitor elements, an inductance element comprising a center conductor of fine wire electrically connecting said capacitor elements, and a hollow dielectric cylinder within which said capacitance and inductance elements are mounted and which is slidably receivable in said tube.

4. A filter as recited in claim 1, wherein the number of said removable filter sections determines the pass band characteristics of the filter.

5. A band pass filter of the coaxial type for use within the microwave range of frequencies comprising a tubular member of electrically conductive material forming the outer conductor and a plurality of removable, unitary, and self-contained filter sections forming the inner conductor, 50 said sections slidably mounted in said tubular member, each of said sections consisting of a hollow dielectric cylinder dimensioned to fit snugly and slidably in said tubular member and having an inductance element and capacitance elements secured thereto and wholly mounted therein, said inductance element being electrically connected to said capacitance elements, and said capacitance elements being capacitively related to said tubular member.
